H. RINGEL.
REINFORCED CORRUGATED PAPER.
APPLICATION FILED DEC. 2, 1918.

Patented Apr. 22, 1919.

INVENTOR
Herman Ringel,
BY
Fred C. Fischer.
ATTORNEY

UNITED STATES PATENT OFFICE.

HERMAN RINGEL, OF NEWARK, NEW JERSEY.

REINFORCED CORRUGATED PAPER.

1,301,605.

Specification of Letters Patent. Patented Apr. 22, 1919.

Application filed December 2, 1918. Serial No. 264,881.

To all whom it may concern:

Be it known that I, HERMAN RINGEL, a citizen of the United States, residing in the city of Newark, in the county of Essex and State of New Jersey, have invented certain new and useful Improvements in Reinforced Corrugated Paper, such as will enable others skilled in the art to which it pertains to make, construct, and use the same, reference being had to the accompanying drawings, and to the characters of reference marked thereon, forming a part of this specification.

This invention relates to new and improved reinforced corrugated paper, and has for its object to provide a corrugated paper that shall be water proof, stretchable, as well as flexible in practically all directions, and which shall be further reinforced so as to adapt itself for use as a protective cover, wrapper or containant.

The object of my invention is to unite, by means of a suitable water proofing cement, two sheets of paper having incorporated therebetween a reinforcing filling as, for instance, some loosely woven fabric, like cheese cloth or any other equivalent thereof, thereby rendering the united sheets impervious to water, moisture or weather conditions; and to further crinkle or crape the said water proofed sheets transversely thereby imparting thereto a transverse stretch of approximately ten per cent., and thereafter crinkling the same longitudinally in order to impart a longitudinal stretch of approximately thirty-three and one-third per cent. to the sheet.

Paper embodying my invention possesses the maximum degree of strength and stretchability and maintains its moisture proof, protecting and cushioning functions throughout the period of use.

In the drawings forming a part of this specification, I have shown,

Figure 1 is a plan view of a piece of my improved reinforced paper, one corner thereof, being separated to show the sheet of cheese cloth or other equivalent thereof, and the water proofing material employed to unite the sheets together.

Fig. 2 represents an edge view thereof, and

Fig. 3 represents on an enlarged scale a transverse section thereof.

Similar characters of reference refer to

like parts throughout the specification and drawings. Referring to the present embodiment of my invention as illustrated in the drawings, my improved paper is preferably made from two sheets of paper 1 and 2, and 60 a sheet of cheese cloth 3, or any other equivalent thereof, united together by means of a suitable water proofing cement 4, in any well known manner common in the art. After the sheets have been so united, which results 65 in a single sheet, the same is passed through a craping machine and craped transversely as indicated at 5, thereby imparting to the sheet a longitudinal expansion of approximately thirty-three and one-third per cent. 70 After the paper has been craped as above described it is passed through a suitable machine and provided with a plurality of longitudinal corrugations 6, which are preferably of such convenient form and size as 75 to impart to said sheet a transverse expansion of approximately ten per cent. or more.

It will be understood that the article of manufacture made in accordance with my invention, is suitable for a variety of purposes, as it has all the qualities of the paper from which it is made, together with the qualities of the cheese cloth, or any other equivalent material thereof, to which the paper is connected. It will now be obvious 80 that any pull exerted longitudinally or transversely upon the paper will cause the crapes or corrugations to flatten and draw apart thereby permitting the paper to stretch in practically all directions. I have also 85 found it desirable to treat one side of the finished article of manufacture as, for instance, the surface of the top sheet of paper, with a water proofing solution, so as to produce a water proof surface. All of these 90 features are highly desirable in a paper which is to be used for baling or wrapping purposes, where the bales, for instance, are subjected to extremely rough and careless handling, and to variable weather conditions.

Experience has demonstrated that the organization above described is a highly efficient one, and while I have shown the preferred embodiment of my present invention, 100 I do not wish to be limited to the exact details of construction shown and described, as obvious modifications thereof, not involving the exercise of invention, may be 105 made by any skilled mechanic, and such de- 110

partures from what is herein set forth, I consider within the scope and terms of my claims.

Having thus described my invention, what 5 I claim and desire to secure by Letters Patent is:—

1. A duplex water proof and craped material consisting of a plurality of sheets of paper, cheese cloth interposed between said 10 sheets and having a water proof compound securing said sheets of paper and cheese cloth.
2. A stretchable wrapping paper capable

of longitudinal and transverse expansion, comprising two sheets of paper and cheese cloth interposed between said sheets of paper united together and rendered impervious to water, said paper being craped transversely and corrugated longitudinally.

This specification signed and witnessed 2 this 21st day of November, 1918.

HERMAN RINGEL.
